UNITED STATES PATENT OFFICE.

LEONARD DANZIGER, OF NEW YORK, N. Y.

PORTFOLIO.

Application filed May 6, 1927. Serial No. 189,377.

This invention relates to portfolios, brief cases and the like, and has for an object to provide an improved construction wherein one or more readily accessible pockets are 5 presented and with means for normally maintaining the pocket or pockets closed.

Another object of the invention is to provide an improved portfolio, brief case or similar article, wherein one pocket may be 10 provided or a number of pockets, and also wherein the single pocket or the plurality of pockets may be provided with one or more removable folders, the entire structure being capable of being closed and maintained normally closed.

A still further object of the invention is to provide in a portfolio, one or more folders capable of movement into and out of a prepared pocket, with means for preventing disconnection of any folder from the portfolio.

In the accompanying drawing—

Figure 1 is a front view of a portfolio, with the flap and flap tying means in an open position, and certain parts broken away 25 for illustrating the interior.

Figure 2 is a view similar to Figure 1, but showing the folder drawn outwardly.

Figure 3 is a sectional view through Figure 1 on line 3—3, the same being on an enlarged scale.

Figure 4 is a vertical sectional view through a portfolio similar to Figure 1, but showing a modified form of folder-holding means.

Referring to the accompanying drawing by numerals, 1 indicates a body which may be formed of leather, artificial leather, cloth or other suitable material, and which is formed with a front section 2 merging into 40 a bottom section 3, which in turn merges into a back section 4. The section 4 is preferably integral with the flap 5, which flap is provided with a lining 6 of cloth or other desired material, said lining extending downwardly into the pocket 7 so as to provide a lining for the various sections 2, 3 and 4.

As indicated particularly in Figures 2 and 3, there is provided a plurality of folders 50 9 in the pocket 7, each folder having an aperture 10 in its bottom near each end, each aperture preferably being supplied with an eyelet whereby the cord or other suitable ligament 11 may slide therethrough. The 55 cord 11 is secured by a rivet or otherwise at 12 to end of the body 1, and also by a rivet

or other means at 13 to the upper part of the end of body 1. It will be understood that the sections 2 and 4 are stitched together at the respective ends 14 and 15, though if desired, some other form of fastening means could be used. It will be understood that a cord or strap 11 is used adjacent each end of the pocket 7, whereby the respective folders 9 may be slid into the pocket 7 or slidly removed therefrom until they reach substantially the outer position as shown in Figure 2. Each folder is preferably provided with a bending line 16 so that when moved to an outer position, as shown in Figures 2 and 3, one side of the folder may be bent back to the dotted position shown in Figure 3, whereby free access may be had to the papers carried by the folder. It is evident that one, two or more 70 folders 9 could be used without departing from the spirit of the invention. Preferably there is provided a cord 11 at each end of the portfolio for each folder so that the respective folders may be readily moved out 75 of the pocket independently. The cords 11 and the arrangement of the apertures 10, prevent the folders from being completely removed but permit a sufficient removal to 80 secure free access to the contents of the folders. When the folders have been moved into the pocket 7 as shown in Figure 1, flap 5 may be folded over the pocket to the dotted position shown in Figure 1, and then the tapes or strings 17 and 18 passed around the body 90 1, after which the tapes are tied, thus holding the pocket 7 against accidental opening. The portfolio or brief structure may be a simple formation as shown in Figure 3, with the ends stitched together or secured together in any desired manner, or may be more elaborate with a folded or plaited end as is 95 commonly found in brief cases now on the market. It is also evident that one or more pockets could be provided in the brief case, and in each pocket one or more folders arranged as above described.

In Figure 4, a modified form of the invention is shown, said modification consisting in the rearrangement of the cords 11'. 105 Aside from the rearrangement of the cords, the construction is identical with that shown in Figure 1 so that the same reference numerals may be used except for the modified parts. In this form of the invention, the 110 cords 11' are secured to the bottom section 3 by suitable rivets 19. The upper ends of the

2
cords 11' extend through suitable apertures 10 in the bottom of the folder and are secured at 20 in any suitable way to the folder. When the folder is pulled out of the pocket 5 as shown in Figure 4, the cords 11' are brought under a slight tension and act to prevent a complete removal of the folders. When the folders are forced back again into pocket 7, the cords 11' will fold substantially 10 as shown in dotted lines.

What I claim is:

1. A portfolio, comprising a body formed of flexible material, a flap extending from one wall of said body adapted when closed 15 to close the body, flexible means for securing said flap in a closed position, a folder normally positioned in said body but capable of sliding movement therefrom, and means associated with said folder for limiting the sliding movement of the folder in 20 one direction.
2. A portfolio, comprising a body defining a pocket, a flap for covering said pocket, a folder adapted to be positioned in said pocket, and flexible means connected with the body and with the folder for limiting the movement of the folder as it is moved out of the pocket.
3. A portfolio, comprising a body defin-

ing a pocket, a flap for closing said pocket, 30 a folder adapted to be positioned in said pocket, said folder being capable of approximate removal from said pocket, and flexible means connected with the folder and with the pocket for limiting the movement of said 35 folder.

4. In a portfolio, brief case or the like, a body formed with a pocket, a folder adapted to be positioned in said pocket, said folder being formed with openings near each end, 40 and a flexible cord extending from each of said openings, said cords being connected with said body whereby the folder may be slid into and out of the pocket but cannot be removed therefrom.

5. In a portfolio, brief case or the like, means defining a pocket, a folder normally positioned in said pocket formed with a pair of openings and a cord for each of said openings, the respective cords extending through the respective openings, and means for securing each end of each cord to said pocket, 50 said securing means being arranged at the bottom and top respectively of the pocket whereby the folder may be slid into and out 55 of the pocket but cannot be removed therefrom.

LEONARD DANZIGER.
